UNITED STATES PATENT OFFICE.

DAVID LIPPY, OF MANSFIELD, OHIO.

CASH AND PARCEL CARRIER.

SPECIFICATION forming part of Letters Patent No. 424,319, dated March 25, 1890.

Application filed September 21, 1887. Serial No. 250,328. (No model.)

To all whom it may concern:

Be it known that I, DAVID LIPPY, a citizen of the United States, residing at Mansfield, in the county of Richland, State of Ohio, have 5 invented certain new and useful Improvements in Cash and Parcel Carriers, of which the following is a specification, reference being had therein to the accompanying drawings.

10 This invention has relation to cash and parcel carriers for store-service apparatus, and the objects and advantages of the same will be hereinafter described, and the novel features particularly pointed out in the claims.

15 Referring to the drawings, Figure 1 is a side elevation of a carriage and track constructed in accordance with my invention, the former mounted for travel upon the latter and being in position to be propelled from a 20 station. Fig. 2 is a longitudinal section on the line *xx* of Fig. 1, showing the means for raising the receptacle to the carriage. Fig. 3 is a transverse section of the track employed. Fig. 4 is a vertical section on the line *yy* of 25 Fig. 1, showing the means for releasing the basket or receptacle. Fig. 5 is a transverse section on the line *ww* of Fig. 1 of the upper portion of the carriage. Fig. 6 is a skeleton view in plan of the top of the car or carriage. 30 Like letters of reference indicate like parts in all the figures of the drawings.

In practicing my invention I provide a track *A* of light rolled steel and form upon the edges of the same longitudinal parallel beads or ribs *A'*. (See Fig. 3.) At each end or terminal of the track are supporting-hangers *B*, the upper ends of which are secured by any suitable means to the ceiling. Intermediate supporting-rods *C*, connected loosely 35 to a base *C'*, secured to the track, are provided at suitable intervals, whereby the track is prevented from sagging.

The carriage or car comprises two end castings *D*, at the upper ends of which are formed 40 or secured cross-heads *D'*, in which are journaled grooved oppositely-arranged parallel wheels or rollers *D*², the grooves of which are adapted to embrace the beads *A'* of the track. Vertical oppositely-arranged pins *D*⁶ 45 (see Figs. 1, 5, and 6) are arranged upon the

cross-heads *D'*, which are centrally slotted at their tops to permit of the passage of the standards and supports of the track. A tie-bar *D*⁴ retains the two castings *D* in relative position, and journaled for rotation within 50 said castings is a shaft *D*⁵, (see Figs. 1 and 2,) upon which are mounted rigidly therewith spools *D*⁶, upon which are wound tapes *D*⁷. Pulleys *D*⁸, mounted for rotation in arms *D*⁹, extending inwardly from the castings *D*, serve 55 to guide the tapes as they are wound upon and unwound from the spools. At the lower ends of these tapes is secured the handle or bail *D*¹⁰ of the basket *D*¹¹. At the right of Fig. 1 is shown the devices as a station for 60 sending articles and cash to the cashier's desk, and the apparatus being suspended overhead it will be understood that the basket must necessarily be lowered to receive such cash and parcels as is desired to transmit to the 65 wrapper or cashier, whose desk being usually elevated no lowering and raising mechanism need be provided. The end, therefore, of the shaft *D*⁵ which is nearest to and toward the station from which the cash or parcel 70 is sent is continued beyond its bearing in the shape of a blade *D*¹², (see Figs. 1 and 2,) and outside of said bearing is provided with a ratchet-wheel *D*¹³, adapted to be engaged by a gravity-pawl *D*¹⁴, terminating in 75 a depending handle *D*¹⁵. (See Fig. 4.) Near the top of each of the castings *D* are formed vertical openings *D*¹⁶, and arranged at each side thereof are rubber rolls *D*¹⁷. A wedge-shaped arm *B'* is arranged to project forwardly 80 from the depending supports *B* and is adapted to pass within the opening *D*¹⁶ and be embraced and impinged upon by the rubber rolls *D*¹⁷, so that an automatic brake is formed, and the cars are gradually brought to a stop, and 85 this without noise or wrenching of the parts.

A rod or bar *B*² projects rearwardly from the support *B*, (in this instance from the arm *B'*), its outer end being supported by a bracket *B*³, having a pulley *B*⁴, journaled therein, 90 and a brace *B*⁵, connecting the same with the upper end of the standard. Depending from the bar *B*² is a bracket *B*⁶, in the lower end of which is journaled a spool *B*⁷, adapted to receive a tape *B*⁸. The shaft *B*⁹, upon which 95

the spool B^6 is journaled and is rigid, is provided at its outer end with a chuck B^9 , (see Figs. 1 and 2,) which is internally bored and provided with ribs or fins B^{10} . The chuck B^9 is arranged in the same plane with the blade D^{12} and is adapted to receive the same when the car enters the station, as shown in Fig. 1. A collar B^{12} depends from the lower end of the support B and is perforated to receive and retain the chuck in position, said chuck being rotatable therein. A rod E connects the collar B^{12} with the bracket B^5 , and depending from the ends of said rod are arms E' , the lower ends of which support a swing- 15 ing wedge-shaped pawl-tripping bar E^2 , at the rear end of which is formed an opening E^3 , through which the tape B^7 passes and hangs down within easy reach of the operator. A boss B^{13} is formed near the front or mouth of the chuck B^9 , which boss abuts against the bracket or collar B^{12} .

At a suitable distance in front of the terminal supports B are supporting-hangers F , which are secured to the track by means of 25 castings F' and are formed with cross-heads F^2 , (see Fig. 5,) having grooved pulleys F^3 , similar to the cross-heads D' of the car, only the former are inverted with relation to the latter, so that the pins D^3 of the heads D' are 30 adapted to pass between the pulleys F^3 , as shown in Figs. 5 and 6. A cord G , one end of which is fixed to the hanger or support B or a portion thereof, or to the side of the cross-head F^2 , extends around in front of the pulleys F^3 , back of the hanger F , and in the path 35 of the pins D^3 of the carriage, and is carried back to the support B , passing over a pulley G' , mounted at one side of the hanger, and extends down within the reach of the operator 40 and is provided with a handle G^2 .

Having described the construction, I will proceed to describe the operation of the apparatus, which is as follows: Taking the carriage in the position shown in Fig. 1, and 45 supposing it is desired to place cash or a parcel, or both, within the basket or receptacle D^{11} , the chuck-tape B^7 is grasped and drawn laterally, which lateral movement causes the pawl-tripping bar E^2 to swing outwardly, 50 and it being in the position shown—that is interposed between the depending handle D^{15} of the gravity-pawl D^{14} —lifts said handle and consequently releases the pawl from the ratchet. The receptacle D^{11} then drops, the tapes 55 D^7 unwinding, and as they unwind rotating the windlass-shaft D^5 , its blade D^{12} , the chuck B^9 , and its shaft and pulley B^8 B^6 , consequently winding up the chuck-tape B^7 upon the latter. The parcel or cash having been placed 60 in the receptacle or basket D^{11} , to elevate the same to the car it is only necessary to pull upon the chuck-tape B^7 , which unwinds and rotates the shaft B^8 , chuck B^9 , blade D^{12} , and windlass-shaft D^5 , thus winding up the tapes 65 B^7 and elevating the receptacle to the position shown. The carriage is now ready to re-

ceive the necessary impetus to carry it to the opposite station. When the carriage comes into the station, the starting-cord G , being in the path of the pins D^3 , is caught and carried 70 by said pins to the rear of the pulleys F^3 . One end of the cord being made fast, as described, it is evident that by drawing upon the free end of the cord G by means of the handle G^2 thereof the tendency of the cord G 75 will be to straighten, and thus give the carriage the throw or impetus to carry it to the opposite station. As it approaches the station, its pins D^3 at the opposite end of the carriage come in contact with the similarly-arranged starting-cord, which cord is caught and doubled by said pins and the operation of starting the carriage is repeated. When the carriage returns to its starting-point, the blade D^{12} enters the chuck, and the receptacle 80 is thus made ready for lowering.

A bail E' is connected to and projects at a right angle from the bracket B^5 and embraces one of the rods E' , thus limiting the lateral swing of the pawl-tripping bar E^2 .

The bail D^{10} has upward bends D^{10x} , which serve to prevent longitudinal swinging of the carrier D^{11} when raised into the frame of the car, while rubber bumpers D^{11x} prevent noise during such operation.

Having described my invention and its operation, what I claim is—

1. A cash-carrier carriage provided with a windlass-shaft having tapes adapted to be wound thereon, said tapes having a cash or parcel receptacle at their other ends, in combination with a ratchet-wheel mounted on said shaft and a pawl designed to take therein and prevent the rotation of the shaft, and with a horizontally-swinging arm adapted to 100 be thrown into contact with the pawl and release the same from contact with the ratchet-wheel, substantially as specified.

2. The combination, with the carriage having the pins D^3 of the track A , intermediate support F , having cross-head F^2 , the cord G , and pulleys F^3 , substantially as specified.

3. A carriage having the end castings D , having the cross-heads D' , provided with the rollers D^2 , having pins D^3 , in combination 115 with the track A , support F , having the cross-head F^2 and pulleys F^3 , and the cord G , arranged upon the pulleys and in the path of the pins, substantially as specified.

4. The combination of the carriage having 120 the pins D^3 , the track A , supports F and B , having the pulleys F^3 and G' , the bracket F^{2x} , and the cord, strap, or tape G , arranged over said pulleys and in the path of the pins, substantially as specified.

5. The carriage D , having the shaft D^5 mounted for rotation therein and formed with the blade D^{12} , in combination with the chuck B^9 , having ribs B^{10} , the shaft B^8 , spool B^6 , and tape B^7 , substantially as specified.

6. The carriage D , having the shaft D^5 arranged for rotation therein and provided with

pawl-and-ratchet mechanism D¹³ D¹⁴, the pawl having the bent handle D¹⁵, in combination with the arm E², substantially as specified.

7. The collar B¹² and bracket B⁵, having the rod E journaled therein, the hangers E', depending therefrom and carrying the arm E², the bail E³, for limiting the swing thereof, in combination with the carriage D, having the rotatable shaft D⁵, having the ratchet D¹³, and

pawl D¹⁴, bent as at D¹⁵, substantially as specified. 10

In testimony whereof I affix my signature hereto in presence of two witnesses.

DAVID LIPPY.
